UNITED STATES PATENT OFFICE.

THOMAS F. VALENTINE, OF CATAWBA, WEST VIRGINIA.

GAUGE.

Application filed February 28, 1925. Serial No. 12,320.

To all whom it may concern:

Be it known that I, THOMAS F. VALENTINE, a citizen of the United States of America, and a resident of Catawba, county 5 of Marion, and State of West Virginia, have invented certain new and useful Improvements in Gauges, of which the following is a full and clear specification.

The object of this invention is to provide a simple tool of the gauge or square type especially for carpenters' use, the construction being such as to enable the carpenter to accurately fit pieces of timber or board into positions in which the ends or 15 edges have irregular or unlike inclinations, as more fully hereinafter set forth.

In the drawing—

Fig. 1 is a plan view of my device with a part in horizontal section;

20 Fig. 2 is an end elevation thereof;

Fig. 3 is another plan view of the device showing it positioned on a board and adjusted for use in making the sawing-lines on a piece of timber;

25 Fig. 4 is a vertical section on the line 4—4 of Fig. 3;

Fig. 5 is a vertical section on the line 5—5 of Fig. 3.

Referring to the drawing annexed by reference-characters, 10 designates a pair of straight-edges pivotally connected together at their inner ends by a base-member consisting of a tube 11 pivotally connected to the inner end of one of the straight-edges 35 and a rod 12 pivotally connected to the inner end of the other straight-edge, this rod being telescoped into the tube and being adapted to be held in its adjusted position by means of a set-screw 13. This base-member is provided with a depending flange 40 14 along its outer longitudinal edge to form an abutment or straight-edge adapted to lie against the edge of the piece of timber on which the sawing-lines are to be drawn by 45 means of the straight-edges 10.

The outer ends of the straight-edges are connected by another extensible member consisting of a tube 15 and a rod 16, the tube and the rod being respectively pivotally connected to the straight-edges, and a set-screw 17 being employed to lock the two telescoping members in their adjusted positions. Extending diagonally from one straight-edge to another is still another extensible member consisting of a tube 18 and a rod 19 respectively connected pivotally to

the straight-edges, a set-screw 20 being employed to lock the parts in their adjusted position.

With the construction above described, it will be observed that by loosening the set-screws, the straight-edges may be adjusted to any angle with respect to each other and also with respect to the base-member and that this adjusted relationship may be maintained by tightening the set-screws, especially set-screw 20. The intermediate extensible member is especially important in that it locks the straight-edges against pivotal movement after the set-screw 20 is set 70 up tight. Without this locking member, it will be observed that the two straight-edges would be free to swing with reference to the base-member, even tho the set-screws 13 and 17 be tightened. It is important also 75 that the locking member shall extend diagonally between the two straight-edges, as otherwise this locking member would partake of the parallel movement that occurs between the base-member and the outer connecting member when the straight-edges are swung in either direction together. I prefer providing the rod 12 with an additional abutment 21 whose inner face 22 is parallel 80 with the inner face of the abutment 14, so 85 as to lie flat against the edge of the timber; this additional or supplemental abutment is promotive of accuracy especially when the telescoping members are extended to a considerable degree. 90

As shown, the rods 12, 16 and 19 may be marked with graduations indicating inches, if desired.

What I claim as new is:

1. In a device of the class set forth, a 95 longitudinally-extensible base-member having a straight-edge face adapted for abutment against the edge of the board, a pair of straight-edges pivotally connected to the opposite ends of said extensible base-member, an extensible connecting member pivotally connecting the outer ends of said straight-edges, and a diagonal longitudinally-extensible locking member connecting the two straight-edges at points intermediate the other pivotal connections therewith, locking means being provided for each one of said extensible members. 105

2. In a device of the class set forth, a longitudinally-extensible base-member having a straight-edge face adapted for abutment against the edge of the board, a pair 110

2

of straight-edges pivotally connected to the opposite ends of said extensible base-member, an extensible connecting member pivotally connecting the outer ends of said straight-edges, and a diagonal longitudinally-extensible locking member connecting the two straight edges at points intermediate the other pivotal connections therewith,

locking means being provided for each one of said extensible members, said straight-edge face being provided with two parts, one being carried by each of the two telescopic members composing the base-member. In testimony whereof I hereunto affix my signature.

THOMAS F. VALENTINE.
